UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

GOVERNING MEANS FOR ELASTIC-FLUID TURBINES.

1,021,212.

Specification of Letters Patent. Patented Mar. 26, 1912.

Application filed September 20, 1907. Serial No. 393,806.

To all whom it may concern:

Be it known that I, RICHARD H. RICE, a citizen of the United States, residing at Lynn, county of Essex, State of Massachusetts, have invented certain new and useful Improvements in Governing Mechanisms for Elastic-Fluid Turbines, of which the following is a specification:

The present invention relates to governing mechanisms for elastic fluid turbines, and has for its object to improve their construction whereby they are rendered more simple and efficacious.

My improved governing mechanism is more especially applicable to elastic fluid turbines of the jet type wherein a plurality of nozzles is provided, which nozzles are successively cut into and out of service as the load changes.

In carrying out my invention a plurality of slightly unbalanced valves is provided, each valve controlling one or more nozzles or fluid conveying conduits. The valves are provided with a common stem and are successively actuated thereby through a lost motion connection, the amount of lost motion between the stem and the valves after the first progressively increasing. That is to say, between the stem and one of the valves is a certain amount of lost motion; between the next valve and the stem is a greater amount of lost motion, and so on, the object being to cause successive operation of the valves both in opening and closing. The first valve to be actuated in admitting steam may be secured to the stem; in any event it moves directly with it.

In order to operate the valves quickly and with precision, and at the same time to avoid the necessity of maintaining a separate source of fluid under pressure, I operate the stem by a steam actuated motor taking steam from the main supply pipe. This motor is controlled by a pilot valve that is responsive to a speed responsive device driven by the turbine. The valve is provided with a follow-up device operated by the motor to restore it to its initial position after a change of speed, which device prevents over-travel of the parts that would result in a fluctuation of the speed of the turbine, this being particularly objectionable where the turbine is employed to drive electrical apparatus. The pilot valve is so set that when it is in its initial position,

steam under pressure has access through restricted openings to the cylinder space on both sides of the motor piston. By reason of this construction, when the valve is moved from its initial position, it immediately and freely admits high pressure fluid to one side or the other of the piston, as the case may be, and subsequently exhausts the fluid from the opposite side. This results in an accumulation of steam in the cylinder which is sufficient to quickly start the piston before the exhaust is opened, thereby avoiding any lag in the operation. The follow-up device is so connected to the piston-rod of the motor and to the governor that any movement of the piston tends to restore the valve to its initial position.

In certain instances it may be desirable to check or retard the movements of the motor piston to prevent them from taking place too suddenly. Where such is the case, a hydraulic dash-pot is provided, comprising a piston and cylinder and a by-pass valve which controls the transfer of liquid from one side of the piston to the other. To insure synchronous operation of the pilot and by-pass valves, they are mounted upon the same stem and both are, therefore, connected to the follow-up device to prevent over-travel. Under certain conditions, however, it may be found desirable to mount the pilot and by-pass valves on separate stems and connect them with the governing mechanism either separately or by a common means. In any event, the parts should be so related one to the other that the dash-pot will prevent too sudden movements of the motor for actuating the valves.

In the accompanying drawings, which are illustrative of the invention, Figure 1 is an end view of a turbine of the Curtis type equipped with my improved governing mechanism; Fig. 2 is a partial side elevation of the same with the valves and their actuating mechanism in section; Fig. 3 is a cross-section taken on line 3-3 of Fig. 2; Fig. 4 is a cross-section taken on line 4-4 of Fig. 2; Fig. 5 is a cross-section taken on line 5-5 of Fig. 2; Fig. 6 is an enlarged longitudinal section of the relay valve for the motor and the by-pass valve for the dash-pot; Fig. 7 is a detail sectional view of the port or passage admitting steam to the motor, the section being taken on line 7-7 of Fig. 3; Fig. 8 is an enlarged detail view

in cross-section of the valve chest showing one of the nozzles for supplying motive fluid to the bucket wheel of the turbine; and Fig. 9 is a longitudinal section of a steam actuated motor and its connection with the governor when the dash-pot is omitted.

Referring to Fig. 1, 10 indicates the casing of the turbine, and 11 the shaft carrying the bucket wheel 12, Fig. 8. Between the 10 rows of wheel buckets are intermediate buckets 13, and steam is supplied to the buckets by a sectionalized nozzle 14, which may be expanding or non-expanding in character.

15 On the main shaft is a worm 15, shown in dotted lines Fig. 1, meshing with worm-wheel 16, the latter being carried by an upright shaft 17. On the upper end of the shaft is a centrifugal governor or speed responsive 20 device 18 which acts through suitable connections on the horizontal lever 19, the lever being pivoted at 20 in lugs formed on the casing inclosing the governor. On the lower end of the shaft 17 is a pump 21 for supplying lubricant to the bearings. Located at one side 25 of the casing around the main shaft is a latch 22 which is adapted to be struck by the moving element of an emergency governor 23 to shut down the machine when, for any reason, 30 the speed becomes excessive. This latch normally engages a device 24 which is mounted on the oscillating stud 25. On the opposite end of the stud is an arm 26 which is pulled in a downward direction by the ex- 35 tension spring 27. The tendency of the spring to act is opposed by the latch 22. Mounted on the front of the casing or valve chest 28 is a steam chest 29 to which steam is admitted by the flanged conduit 30. Located 40 within the steam chest and loosely mounted on a spindle 31 is an emergency valve. On the spindle 32 is mounted a tripping device 32^a inside the chest and an arm 32^b outside, which latter is connected through 45 a pin-and-slot connection with the rod 33. When the emergency governor 23 trips the latch 22, the spring 27 exerts its force on the rod 33 and by reason of the lost motion, it acts on the arm 32^b with a hammer blow and 50 closes the emergency valve. In order to reset the emergency valve a handle 34 is provided which is located on the side of the steam chest. It is normally held in the position shown by the extension spring 35. Rotating the handle from the position shown 55 resets the emergency valve and the device 32^a.

Referring more particularly to Fig. 2, 28 indicates the casing of the controlling valve which receives steam adjacent its upper end 60 from the conduit 30 and is covered with any suitable non-conducting lagging 28^a. This casing is provided with a series of ports 40, 41 and 42, each leading to one or more sections of a sectionalized expanding or non-expanding nozzle, as the case may be. The

casing is also provided with a conical bore at its lower end, and located therein is a sleeve 43 which is provided with two seats 70 for each of the valves, and also with passages or ports 44 communicating with the ports in the valve casing. By using a sleeve 75 the seats can be accurately formed and the ports or passages 44 made without difficulty to the required dimensions, and they may also be accurately located one with respect 80 to the other. By making the bore of the casing and sleeve conical the sleeve can readily be forced into place under pressure and does not require additional holding means. By using a conical sleeve for the seats, individual valves can be employed which may be slipped into place one after the other. The diameters of the valves and seats are so arranged that this action can take place. By 85 using a support that is common to all of the seats the danger of faulty operation, due to 90 improper alignment or adjustment, is avoided.

The bore at the upper end of the valve casing is cylindrical, and located therein is 90 a frame comprising upper and lower heads 45, which heads receive the upright frame bars 46, the latter being connected by an annular ribs 47. Surrounding the frame is a screen 48 to prevent foreign matter from 95 being carried into the turbine from the source of steam supply. The lower head 45 is provided with a gutter in its upper surface in which foreign matter will collect. The diameter of the lower head is such that 100 when the frame and the screen are removed, it will scrape the bore of the casing, and thus remove any and all foreign particles carried in with the steam.

Located within the bore of the casing is a 10 valve stem 49 which is provided with a series of steps or shoulders that form abutments for moving the valves successively. The upper end of the stem is provided with 11 a guide 50 carried by the frame of the screen. The valves 51 are loosely mounted on the stem and the amount of lost motion between each valve and its abutment increases from the top to the bottom. The upper valve is shown as resting on its abutment, and it is the first valve to open. The second one is separated from its abutment by a small space, and the third valve is separated by a greater space. The valves are 12 of the double seat type with passages permitting steam to pass from the upper part of the valve-chest or casing downward through their interiors and are made as nearly balanced as possible. There is, however, a slight unbalanced effect due to the 13 difference in areas of the upper and lower seats of each valve. This is sufficient to cause the valves to seat when the stem is lowered a sufficient amount.

Situated below the valve chest is a frame 14

or casing 52 containing a cylinder 53 for the steam actuated motor and a cylinder 54 for the hydraulic dash-pot. Located within the steam cylinder, and mounted on a shouldered extension of the valve stem is a piston 55. Situated above the piston and forming the upper part of the cylinder is a head 56 which in the present instance is clamped between the main portion of the valve casing and the frame or extension 52 located below it. This head is provided with a sleeve surrounding the valve stem for reducing the leakage between the steam space below the valves and the cylinder space above the piston. Situated below the piston and located in the lower head of the cylinder is a packing 57 of any suitable construction. The upper and lower heads of the cylinder of the dash-pot are likewise provided with packings 58 to prevent the escape of fluid.

Located within the dash-pot cylinder and mounted on the stem 49 is a piston 59, and between it and the motor piston is a spacing sleeve 60. Between the piston 59 and the nut on the end of the stem is a spacing sleeve 61. When the nut is screwed into place both pistons and the sleeves are locked in place. Below the nut is a bracket 62, Fig. 5, to receive the pivot pin 71 for the lever of the follow-up device, the said bracket being held in place by a nut 63. The distance between the axis of the pin 71 and that of the stem 49 will be greater or less depending upon the total movement of the speed governor from no load to full load conditions. On the right-hand side of the pistons the casing is bored in a direction parallel with the axis of the motor to receive the valve bushings 65 and 66. These will be referred to more especially in connection with Figs. 3 to 7 inclusive. The bushings 65 and 66 are bored to receive the pilot valve 67 and the by-pass valve 68. A single stem 69 is provided for these valves and is pivotally connected to the lever 70. One end of this lever is pivotally connected at 71 to the piston rod of the motor and at the other end is connected by the pivot 72 with the vertically extending and adjustable connecting rod 73. The upper end of this rod is connected to the horizontal governor lever 19, best shown in Fig. 1. The lever 70 is provided with a guide 70^a to direct it in its vertical movements.

Referring now to Fig. 6, 55 indicates the steam actuated piston and 67 the pilot valve for controlling it. This valve is of the balanced piston type and steam is admitted to the space 74 between the heads by the vertical passage 75, Figs. 3 and 7, and the horizontal passage 76. The adjacent sides of the heads are slightly farther apart than the adjacent edges of the ports in the bushing 65 that lead to the cylinder 53 (as best seen from Fig. 2), so that when the valve is in

its initial or middle position steam is admitted to both ends of the cylinder and the piston is ready to start quickly whenever either port is opened to exhaust and closed to steam by a slight displacement of the valve. The passage 75 communicate with the space at the bottom of the valve-chest 28 directly under the controlling valves, and is therefore in direct communication through the interior of the valves and chest with the steam supply conduit 30. Partially surrounding the bushing 65 is an exhaust chamber 77 communicating with the exhaust port 78. As shown, steam is being admitted to the under side of the piston 55 and the opposite side of the piston is open to the exhaust. Situated below the pilot valve and on the same stem is a by-pass valve 68 for controlling the hydraulic dash-pot. This valve is also of the piston type and is intended to control the passage of fluid around the piston 59. As shown, the liquid is in the act of passing from the upper side of the piston through the port 79 into the space 80 around the sleeve, and thence through the port 81 to the under side of the piston 59. Just as soon, however, as the pilot valve is restored to its initial position, the by-pass valve will be moved to the position to close the ports of the dash-pot and its piston will be locked in place. In order to supply liquid to this dash-pot for the purpose of replenishing the supply in case of leakage or to supply it initially, an inlet pipe 82 is provided. It will be noted that one stem is provided for both of these valves, and that they act simultaneously. In order that the parts may be disconnected, a joint 83 is provided in the stem so that the dash-pot mechanism can be disconnected without taking off the pilot valve.

In Fig. 9 is shown the construction when the hydraulic dash-pot is omitted. To the end of the rod or stem 49 is screw-threaded the cap 84, which contains the head of the rod 85. This rod forms an axial continuation or extension of the stem 49 and passes through a long packing sleeve 86 to prevent the escape of steam from the cylinder. To the lower end of the rod is secured a bracket 62 to which is connected, by the pivot 71, the lever 70, the latter in turn being connected to the governor. The total movement of the governor in this illustration is assumed to be different from that previously described, hence the distance between the axes of the stem 49 and pivot 71 is different from that in Figs. 2 and 5. The construction and arrangement of the pilot valve and the steam passages and ports co-operating therewith to control the movements of the piston 55 are the same as that of the similar parts shown in Figs. 2, 3, 6 and 7 and previously described. The exhaust from the cylinder escapes by the pipe 78 to a con-

denser or to the atmosphere, as desired. The lower end of the pilot valve is pivotally connected to the lever 70, and the latter is provided with a guide 87 to direct it in its 5 vertical movements.

The operation of my improved mechanism is as follows:—Assuming that the turbine is in operation and one valve is open and the load increases. The governor will 10 depress the rod 73. This moves the relay valve 67 and the by-pass valve 68 down, and steam is admitted to the under side of piston 55, Figs. 2 and 6. This causes the latter to move upwardly and carry with it 15 the second valve, and thus more steam is admitted to the turbine. As the piston 55 moves upwardly it carries with it the piston 59, and the liquid above the latter piston is conveyed through the passages and ports 20 past the valve 68 to the under side of the piston. As the motor piston begins to move, it carries with it the pivot 71 of the lever 70, the pivot 72 now becoming the fulcrum. This action continues until the valves 25 67 and 68 close the ports, when the motor will cease operating and a body of fluid will be confined above and a second body below the dash-pot piston 59. A further increase in load will open the third valve, or a greater 30 number of valves, if the turbine is so provided. On the other hand, if the load decreases, the valves will close, one after the other, and the valves 67 and 68 will be moved accordingly. On a decrease in load 35 these valves are moved upwardly at the start and subsequently downward by the movement of the motor piston.

In accordance with the provisions of the patent statutes, I have described the principle of operation of my invention, together with the apparatus which I now consider to represent the best embodiment thereof; but I desire to have it understood that the apparatus shown is only illustrative, and that 45 the invention can be carried out by other means.

What I claim as new, and desire to secure by Letters Patent of the United States, is,—

1. In a governing mechanism for turbines, 50 the combination of a plurality of individual valves, a stem common thereto, a lost motion connection between the valves and the stem, the amount of lost motion between them progressively increasing toward one end of 55 the stem, and means responsive to load changes which actuates the stem to move the valves successively.

2. In a governing mechanism for turbines, 60 the combination of a plurality of individual valves, a stem upon which the valves are loosely mounted, means on the stem for moving the valves one after the other, a motor for actuating the stem, and a load responsive device for controlling the motor.

3. In a governing mechanism for turbines, 65

the combination of a plurality of individual valves, seats therefor, a stem upon which the valves are loosely mounted, abutments on the valve stem which have different spacing than the valve seats to cause successive opening and closing of the valves, a fluid actuated motor for moving the stem, a pilot valve controlling the motor, and a governor controlling the valve. 79

4. In a governing mechanism for turbines, 75 the combination of a plurality of individual valves, a stem upon which the valves are loosely mounted, means on the stem for moving the valves one after the other, a motor for actuating the stem, a load responsive device for controlling the motor, and a follow-up device for preventing over-travel of the motor and the valves. 80

5. In a governing mechanism for turbines, 85 the combination of a valve, a fluid actuated motor for moving the valve, a pilot valve controlling the motor which in its initial position admits motive fluid to both sides of the motor piston, means for exhausting fluid from the motor which becomes effective 90 when the valve is displaced from said initial position, and a governor for controlling the valve. 95

6. In a governing mechanism for turbines, 95 the combination of a valve, a fluid actuated motor for moving the valve, a pilot valve controlling the motor which in its initial position admits motive fluid to both sides of the motor piston, means for exhausting fluid from the motor, a governor for controlling 100 the valve, and a follow-up device for preventing over-travel of the motor.

7. In a governing mechanism for turbines, 105 the combination of a plurality of valves, a steam actuated motor for moving the valves one after the other, a pilot valve for controlling the motor which returns to its initial position after moving each of the valves and when in said position admits fluid to both sides of the motor piston, a governor 110 for the pilot valve, and a follow-up device for restoring the pilot valve to its initial position.

8. In a governing mechanism for turbines, 115 the combination of a valve chest, a plurality of double-seat valves located therein which are partially balanced with a tendency to close, a stem which is common to the valves and moves them one after the other through lost motion connections, a fluid actuated 120 motor connected to the stem, a pilot valve for the motor, and a governor for controlling the pilot valve.

9. In a governing mechanism for turbines, 125 the combination of a valve chest, a plurality of double-seat valves located therein, a sleeve containing seats for the valves, a stem common to the valves which is provided with abutments to engage the valves which are differently spaced than the valve seats, a 130

motor for actuating the stem, and a governor for the motor.

10. In a governing mechanism for turbines, the combination of a valve chest, a plurality of individual valves therein, a motor for actuating the valves successively including a cylinder affixed to the chest, there being ports communicating with the cylinder space, a piston in the cylinder for actuating the valves, a piston rod which projects through the cylinder head and forms a stem for the valves, means for mounting the valves on the stem for movement one after the other, a pilot valve for controlling the flow through said ports, a lever connected to the piston rod and to the pilot valve, and a governor also connected to said lever.

11. In a governing mechanism for turbines, the combination of a plurality of valves, a stem which is common to the valves and moves them one after the other through lost motion connections, a fluid-actuated motor for moving the stem, a liquid-containing dash-pot for preventing too sudden action of the motor, and a governor which controls the motor and also the dash-pot.

12. In a governing mechanism for turbines, the combination of a plurality of valves, a stem which is common to the valves and moves them one after the other through lost motion connections, a fluid-actuated motor for moving the stem, a liquid-containing dash-pot for preventing too sudden action of the motor, a pilot valve for the motor, a controlling valve for the dash-pot, and a governor which controls both of said valves.

13. In a governing mechanism for turbines, the combination of a plurality of individual valves, a stem common thereto, a motor which actuates the valves successively, a liquid-containing dash-pot which operates each time a valve is moved and prevents too sudden movements of the motor piston, and a governor which controls the action of both motor and dash-pot.

14. In a governing mechanism for turbines, the combination of a plurality of controlling valves having a common stem, means including a motor for actuating the valves successively, a dash-pot which prevents too sudden movements of the motor, and a governor which controls the action of the dash-pot.

15. In a governing mechanism for turbines, the combination of a plurality of controlling valves, a fluid-actuated motor for

moving the valves one after the other, including a cylinder and a piston, a valve casing in axial alignment with the cylinder, a common stem for the valves which projects from the casing and forms a piston rod for the motor, a hydraulic dash-pot, a pilot valve for the motor, a by-pass valve for the dash-pot, and a governor which actuates both valves.

16. In a governing mechanism for turbines, the combination of a plurality of individual controlling valves, a fluid actuated motor for moving the valves successively, including a cylinder, a piston, and a piston rod which also forms a stem for the valves, a hydraulic dash-pot, a pilot valve for the motor, a by-pass valve for the dash-pot, a stem common to both valves, and a speed governor which actuates the stem.

17. In a governing mechanism for turbines, the combination of a plurality of individual controlling valves, means including a fluid-actuated motor for moving the valves successively, a hydraulic dash-pot, a pilot valve for the motor, a by-pass valve for the dash-pot, a governor which actuates both valves, and a means actuated by the motor for restoring the pilot and by-pass valves to their initial positions to prevent over-travel of the controlling valves.

18. In a governing mechanism for turbines, the combination of a plurality of individual valves, an independent seat for each valve, a stem which passes through the valves and raises them from their seats one after the other when moved in one direction, and which permits them to close by fluid pressure one after the other when moved in the opposite direction, a motor that is connected to the stem for moving it, and a governing means for regulating the operation of the motor.

19. In a governing mechanism for turbines, the combination of a valve chest, a valve located therein, a strainer located in the bore of the chest, a head for the strainer which makes a snug fit with the bore so as to scrape it when removed and take out foreign matter.

In witness whereof, I have hereunto set my hand this eighteenth day of September, 1907.

RICHARD H. RICE.
